UNITED STATES PATENT OFFICE.

OSCAR WOODWARD, OF NEW YORK, N. Y., ASSIGNOR TO YOST WRITING MACHINE COMPANY,
OF ILION, NEW YORK, A CORPORATION OF NEW YORK.

TYPE-WRITING MACHINE.

No. 893,827.

Specification of Letters Patent.

Patented July 21, 1908.

Application filed February 16, 1907. Serial No. 357,609.

To all whom it may concern:

Be it known that I, OSCAR WOODWARD, citizen of the United States, and resident of the borough of Manhattan, city of New York, in the county of New York and State of New York, have invented certain new and useful Improvements in Type-Writing Machines, of which the following is a specification.

My invention relates to typewriting machines, and more particularly to means operable at will for maintaining the types out of contact with the inking pad to facilitate the removal from and the introduction of an ink pad into the machine.

15 To the above and other ends which will hereinafter appear my invention consists in the features of construction, arrangements of parts and combinations of devices to be hereinafter described and claimed.

20 In the accompanying drawings, Figure 1 is a fragmentary, central, vertical, front to rear sectional view showing sufficient number of parts of one form of typewriting machine to illustrate my invention; the view illustrating the parts in the normal position with the locking bar or plate in the inoperative position. Fig. 2 is a like view of the same with some of the parts omitted and with the locking bar in the operative position. Fig. 3 is 25 an enlarged detail fragmentary vertical sectional view showing a portion of the locking mechanism. Fig. 4 is a detail fragmentary top plan view with parts broken and sectioned away of the means for locking the key 30 levers depressed.

While I have illustrated my invention applied to a front-strike typewriting machine embodying a type action of the same specific character as that disclosed in the application 35 of George F. Balloa, filed January 22nd, 1907, Serial No. 353,558, and of the same general character as that shown in the application of Arthur W. Smith, filed May 15th, 1905, Serial No. 260,441, it should be understood 40 that the invention may be applied to other styles of typewriting machines.

The frame of the machine comprises a base 1 provided with corner posts 2 and a top plate 3. Any suitable carriage (not shown) 45 is provided with a platen 4 diagrammatically shown in Fig. 1, the carriage traveling from side to side of the machine in the usual manner. A segment 5 has radially disposed hangers 6 secured thereto by screws 7. Each 50 hanger has a driver 8 pivoted thereto at 9

and each hanger is pivoted at 10 to a type bar proper 11. The forward end of each type bar is pivoted at 12 to a guide link 13. The guide links of the system of type bars are pivoted on a pivot wire 14, each guide link 60 being received and guided in a radial slot 15 in a segment 16. A pull link 17 is connected at its rear end 18 to the associate driver 8, the forward end of the link being connected at 19 to a bell crank sub-lever 20. The sub-levers are each pivoted at 21 to a hanger 22 secured by a nut 23 to a segment 24. The forwardly projecting arm of each bell crank sub-lever 20 is connected to the upper end of a link 25, the lower end of which is connected 7 at 26 to an associate key lever 27. The key levers 27 are all pivoted on a pivot rod 28 secured to depending arms 29 which form part of a frame comprising the segments 5 and 24. Each key lever is provided with a finger key 7 30 and an upwardly projecting arm or member 31 which latter is received in a slot 32 formed in a guide or comb plate 33. The comb plate forms part of an angular plate 34 secured by screws 35 to brackets 36. Brackets 37 are secured by screws 38 to the angular plate 34 near each side of the machine and are provided with bearings 39 for the reception of a rock shaft 40. This rock shaft 40 is grooved throughout its length for the reception of a locking bar or plate 41 which extends substantially throughout the length of the bar and throughout the width of the keyboard of the machine, as shown in Fig. 4.

The right-hand end of the rock shaft 40 is bent to form a crank arm 42 provided with a finger piece 43 by which the rock shaft may be turned in its bearings to move the locking bar to and from operative position, the inoperative position of the locking bar being shown in Fig. 1 and the operative position of the locking bar being shown in Fig. 2. The locking bar is apertured near the right-hand end thereof at 44 for the reception of the reduced end 45 of a leaf spring 46, the other end of the leaf spring being secured by screws 47 to the under side of the angular plate 34. The construction is such that the tension of the leaf spring is exerted against the upper wall of the slot 44 of the locking bar to maintain said bar in the inoperative position when it is turned to such position through an actuation of the finger piece 43, as indicated in Fig. 3. This same spring likewise bears against the upper wall of the

slot when the finger piece 43 is turned to the position shown in Fig. 2 to maintain the locking bar against accidental displacement in the operative position. The spring at this time exerts a pressure towards the axis of the rock shaft, thus tending to prevent the locking bar from turning from the operative position. The shoulders 46^a on the spring 46 abut the locking plate 41 at each side of the aperture 44 therein and limits the forward movement of the plate. The types 48 normally bear against the inking pad 49 contained in a case 50 which may be detachably secured to the frame of the machine. The inking pad may likewise be detachably mounted in its trough-like case 50. One inking pad may be removed and another substituted therefor at will, either by removing the inking pad from its case or by lifting the case and the inking pad together out of the machine and substituting a new inking pad for the one which is exhausted. In order to facilitate the removal of the inking pad it is desirable or necessary to remove all of the types 48 from contact with the inking pad. It is for this purpose that the so-called locking bar 41 is provided. When the locking bar is in the inoperative position shown in Fig. 1 the types normally rest on the ink pad and are free to be actuated and to be moved to the printing position as indicated by the dotted line in Fig. 1 at each depression of a key 30. When it is desired to remove the inking pad the finger piece 43 is moved rearwardly from the position shown in Fig. 1 to that indicated in Fig. 2. The effect of this movement is to turn the locking bar around an axis substantially coincident with one edge thereof and to simultaneously depress all of the key levers to the positions shown in Fig. 2, thereby moving all of the jointed type bars sufficiently to carry the types out of contact with the inking pad as shown in Fig. 2 to facilitate a removal of the pad. When a new or re-inked pad has been introduced into the machine the finger piece 43 is again moved to the position shown in Fig. 1, thereby releasing all of the key levers and enabling the types to again contact with the inking pad.

What I claim as new and desire to secure by Letters Patent, is:—

1. In a front-strike typewriting machine, the combination of an ink pad, a plurality of segmentally arranged upwardly and rearwardly striking jointed type bars normally resting against the face of the ink pad, key levers for actuating said type bars, a hand-controlled device pivoted to the frame of the machine and coöperative with all of said key levers to maintain them partly depressed so that the type bars may be maintained off the ink pad, and means for maintaining said device either in or out of coöperative relation with said key levers.

2. In a typewriting machine, the combination of an ink pad, a series of type bars normally resting on said ink pad, key levers for said type bars, a locking bar pivoted substantially in line with one edge thereof to the main frame of the machine and coöperative with the key levers of the entire system of type bars to maintain said key levers depressed and the type bars away from the ink pad, and a finger piece for controlling the movement of said bar on its pivotal center into and out of coöperative relation with said key levers.

3. In a typewriting machine, the combination of an ink pad, a series of type bars normally resting in said ink pad, key levers for said type bars, a locking bar pivoted substantially in line with one edge thereof to the main frame of the machine and coöperative with the key levers of the entire system of type bars to maintain said key levers depressed and the type bars away from the ink pad, a finger piece for controlling the movement of said bar on its pivotal center into and out of coöperative relation with said key levers, and a spring for retaining the locking bar in either the operative or inoperative position.

4. In a typewriting machine, the combination of an ink pad, a series of type bars normally resting in said ink pad, key levers for said type bars, a locking bar pivoted substantially in line with one edge thereof to the main frame of the machine and coöperative with the key levers of the entire system of type bars to maintain said key levers depressed and the type bars away from the ink pad, a finger piece for controlling the movement of said bar on its pivotal center into and out of coöperative relation with said key levers, a perforation formed in the locking bar, and a leaf spring that extends through said perforation and bears against an edge thereof and retains the locking bar in either the operative or inoperative position.

5. In a typewriting machine, the combination of an inking pad, a series of type bars normally resting on said inking pad, a series of key levers for actuating said type bars, a rock-shaft journaled in bearings in a fixed portion of the machine, a plate fixed to said rock shaft and adapted to depress the key levers of the entire system of type bars when the rock-shaft is turned, and a finger piece connected with said rock shaft and by means of which the plate is moved to the operative and inoperative position.

6. In a typewriting machine, the combination of an inking pad, a series of type bars normally resting on said inking pad, a series of key levers for actuating said type bars, a rock-shaft journaled in bearings in a fixed portion of the machine, a plate fixed to said rock shaft and adapted to depress the key levers of the entire system of type bars when

the rock-shaft is turned, a finger piece connected with said rock shaft and by means of which the plate is moved to the operative and inoperative positions, and a spring co-
5 acting with said plate to retain it either in the operative or inoperative position.

Signed at the borough of Manhattan, city

of New York, in the county of New York,
and State of New York, this 15th day of Feb-
ruary, A. D. 1907.

OSCAR WOODWARD.
